APPARATUS FOR CONTROLLING THE LEVEL OF LIQUIDS

Application filed May 8, 1930. Serial No. 450,653.

This invention relates to liquid level control and more particularly to thermostatic means for controlling the liquid level in a container by regulating the discharge of fluid 5 therefrom.

Although the present invention is applicable to different forms of apparatus, it has been developed principally for controlling the liquid level in high pressure liquid containers or chambers, such as condensers, used, for example, on refrigeration systems of the compression type and will be described as applied to such a system.

The condensed refrigerant in liquid form 15 is collected in high pressure receptacles or containers, such as condensers, in the high pressure side of such compression systems, and for uniform and efficient operation the liquid level in such containers should be maintained substantially the same during operation. Heretofore, it has been proposed to control the liquid level by using float valves. For example, there are systems in each of 20 which the refrigerant (which may consist of any suitable material, such as ammonia, sulphur dioxide, methyl chloride or carbon dioxide) is condensed to liquid form in a condenser, and drained immediately into a small float valve trap, liquid refrigerant being discharged from said trap into the low pressure 25 side of the system each time the liquid in the trap rises to a predetermined level.

The float valve controls have, however, given 30 considerable trouble and they are subject to various disadvantages. For example, the valve in each of such systems must be located adjacent to or immediately below the condenser or receptacle and must be connected with one or more cooling devices or refrigerators by one or more low pressure, low temperature lines which must be thermally insulated, as by use of cork.

The general object of the present invention 40 is to provide an improved liquid level control. A further object is to provide an improved liquid level control for high pressure containers or receptacles. Another object is to provide thermostatic liquid control means for this purpose.

The aforesaid and other objects are at-

tained by apparatus of which a preferred embodiment is illustrated in the accompanying drawing, in which: Fig. 1 is a fragmentary elevation of a refrigerating system embodying one form of the invention, parts being broken away to show the underlying structure; and Fig. 2 is a central vertical section of the expansion valve.

Referring to the drawing, the hot discharge gas from a compressor (not shown) is conducted through a pipe or conduit 10 to one end of a tube or tube section 11 arranged horizontally at the side of a receptacle or condenser 12, which may be of shell and tube construction, and said discharge gas is conducted from the other end of said tube section 11 through a pipe 13 to the top of the condenser 12. From the bottom of the condenser, liquid collected in the condenser passes through a pipe 14 to the high pressure side of a suitable expansion or pressure reducing valve 15, and enters a chamber 16 closed at its upper side by a diaphragm 17.

The liquid refrigerant at condenser pressure acts on the lower side of the diaphragm 17 and tends to flex it upwardly and thereby permit a valve member 18 to be lifted, by suitable means including a spring 19, out of engagement with a valve seat 20 forming the bottom of the chamber 16 in the valve body. Upon such lifting of the valve or valve member 18, a port 21 in the valve seat 20 will be opened thus permitting the compressed refrigerant to pass downwardly through the port and to the outlet 22 at the low pressure side of the expansion valve 15.

At the upper side of the diaphragm 17 is a chamber 23 enclosed between the diaphragm and the lower surface of a cover 24 which engages the diaphragm near the periphery thereof and is clamped to the upper part of the valve body by suitable means, such as bolts 25, thus gripping the diaphragm at its periphery and holding it in position. The diaphragm is also subjected to pressure at its upper side through a pipe or line 26 connected at one end with an opening 27 in the cover 24 and at the other end with a thermal unit or chamber 28 surrounding the horizontal tube sec-

tion 11 and surrounded in turn by a chamber or jacket 29.

At its bottom and preferably near one of its ends, the jacket 29 is connected with 5 one end of a pipe 30 of which the other end is connected with the condenser 12 at the bottom thereof. At its top and preferably near its other end the jacket is connected by a pipe 30a with the condenser 12 at a point 10 above the liquid level in said condenser. For the purpose of providing a suitable charge of elastic fluid in thermal chamber 28, line 26 and chamber 23 of the valve, the pipe or line 26 may be connected with the high pressure line or pipe 14 through a pipe 31 containing a valve 32. In charging this part of the system, the valve 32 is opened so as to produce the desired pressure and when the desired pressure is indicated on a gauge 33 15 connected with the pipe 26, the valve is closed.

The thermostatic valve 15 is of simple form as here disclosed. In order that the valve may be tightly closed, the main body 25 of the movable valve member 18 is tapered to fit closely against the correspondingly tapered upper end of the port 21. For guidance and operation, the valve member 18 may be provided at its upper end with a reduced extension which fits into an opening or recess at the lower side of a diaphragm pusher 34 which is suitably guided in the upper part of the valve body and is provided at one point of its periphery with a 30 recess or opening 35 to assure communication between the chamber 16 and the lower surface of the diaphragm 17.

The valve member 18 is also provided at 40 its lower end with a reduced extension which fits into an opening in the upper end of a longitudinally movable member 36 engaged at its lower end by the spring 19. The member 36 is slidably mounted in a plug 37 screwed into the lower side of the valve body 45 and the spring 19 is housed in a tubular extension of said plug. To avoid interference with the operation of the member 36 communication between the interior of the valve and the interior of the tubular extension of 50 the plug 37 may be effected in any suitable manner, as by providing a groove 37a in member 37. At its lower end the spring is engaged by a spring cap 38 located on the upper end of a screw or spindle 39 having a 55 threaded upper end screwed into a plug 40 which in turn is screwed into the lower end of the spring-containing tubular portion of the plug 37. Leakage around the spindle may be prevented by use of packing 41 in a 60 suitable opening in the lower end the plug 40, the packing being engaged by a packing gland 42 forced inwardly against the packing by means of a cap 43 placed over the spindle and screwed on the lower end of said 65 plug 40.

The operation will now be described. Valve or valve member 18 controls the port 21 in the seat 20 and is moved up or down in accordance with the movement of diaphragm 17. Pressure from the thermal unit or chamber 28 prevails at the upper side of the diaphragm, and condenser pressure prevails at the lower side of the diaphragm. The spring 19 exerts upward pressure on the valve or valve member 18 and therefore acts on the diaphragm in opposition to the pressure from the thermal unit. Suitable adjustment of the spring pressure may be effected by means of the screw or adjusting spindle 39.

When the thermal unit pressure equals the condenser pressure, the expansion valve opens under the influence of the spring 19. When the liquid level in the condenser falls following discharge of liquid to the low pressure side of the system, the thermal unit pressure increases under the influence of hot gas in the inner tube 11 and overbalances both the condenser pressure and the spring pressure, thus closing the expansion valve. Then the liquid again accumulates in the condenser and flowing through the tube or pipe 30 enters the jacket 29 and surrounds a greater part of the thermal unit 28 than before, thus cooling the thermal unit and reducing the pressure therein.

Such reduction of pressure in the thermal unit causes the pressure at the upper side of the diaphragm to be overbalanced by the combination of condenser and spring pressures and the valve to be opened. Liquid refrigerant lying at a certain level in the jacket 29 is caused to boil at the condensing pressure by heat received from the thermal unit. The gas given off by this boiling leaves the jacket very freely through the pipe 30a and therefore permits such boiling at the same pressure as prevails in the condenser.

It will be apparent that, in a system equipped with a liquid level control embodying the present invention, the expansion valve may be located at any desired level. Furthermore, inasmuch as the line from the condenser to the expansion valve is a high pressure and high temperature line and the valve may be located close to a cooler or the like, there is no necessity for the considerable amount of heat insulating covering which is required in connection with the usual forms of liquid level controls.

I claim:

1. In a refrigerating system, the combination with a condenser, a conduit to withdraw condensed liquid refrigerant from said condenser and a thermostatic valve controlled by a diaphragm and controlling such withdrawal of liquid refrigerant, of a conduit for supplying refrigerant vapor to said condenser and having a horizontal portion at a predetermined level for the maintenance of

liquid level in said condenser; a jacket forming thermal chamber surrounding such vapor supplying conduit and connected with said valve at one side of said diaphragm to 5 open said valve upon decrease of pressure in said thermal chamber and to close said valve upon increase in pressure, said jacket around said thermal chamber being connected at its lower part with the liquid containing part 10 of the condenser and at its upper part with the vapor containing part of the condenser.

2. A combination of apparatus of the character described, comprising a thermal unit, a condenser, a valve, a diaphragm in 15 said valve, means for exerting a pressure on one side of said diaphragm responsive to temperature changes in said thermal unit, means for applying pressure to the other side of said diaphragm responsive to changes in 20 condenser pressure within the condenser, a spring within the valve, said spring being arranged to exert a pressure on said diaphragm in combination with said pressure from the condenser, in opposition to the pressure exerted upon said diaphragm from the 25 thermal unit.

3. A combination of apparatus for controlling the level of liquid in a condenser comprising a supply passage for said condenser, a thermal unit, a valve, a first chamber surrounding said supply passage comprising part of said thermal unit and containing a fluid, a diaphragm within the 30 valve, means for connecting said first chamber to one side of said diaphragm, a second chamber surrounding said first chamber and connected to said condenser, means for connecting said condenser to exert a pressure responsive to changes in condenser pressure on the other side of said diaphragm, and a spring within the valve for causing 35 said valve to function responsive to changes in said pressure, the functioning of said valve controlling the level of the liquid within the condenser.

4. A condenser and means for controlling

the level of liquid therein, comprising a supply passage for said condenser, a thermal unit surrounding said supply passage, said unit having two chambers, a valve, one of 70 said chambers being connected to the condenser, the other chamber being connected to the valve, said condenser being connected to the valve and means in combination with the valve for controlling the level of liquid within the condenser responsive to changes in 75 pressure within said unit and within the condenser.

5. In a refrigeration system having a condenser, means for controlling the level of refrigerant within the condenser comprising a thermal unit, a jacket surrounding said unit and connected to said condenser at a plurality of points, a valve, a diaphragm within the valve, means for admitting liquid from 80 said condenser to exert a pressure on one side of said diaphragm, means for charging said unit with refrigerant at a desired pressure, means for connecting said unit to the other side of the diaphragm, means for varying the pressure in said unit responsive to changes in 85 temperature in said jacket surrounding said unit, said valve being arranged to control the level of liquid within the condenser whenever the pressure in the thermal unit is at a predetermined variance from the condenser 90 pressure.

6. A container and means for controlling the level of liquid therein comprising a supply passage for said container, a thermal unit surrounding said supply passage and parallel to the level of liquid in said container, a valve, a diaphragm in the valve, means for admitting liquid from said container to exert a pressure on one side of said valve, means for connecting said unit to the other side of said valve, a jacket surrounding said unit, and means for connecting said jacket to said container at a point below the desired liquid level and at another point 100 above the desired liquid level.
